UNITED STATES PATENT OFFICE.

ARTHUR J. LANGLOIS AND WILLIS H. MANSFIELD, OF HAVERHILL, MASSACHUSETTS, ASSIGNEES TO UNITED SHOE MACHINERY CORPORATION, OF PATERSON, NEW JERSEY, A CORPORATION OF NEW JERSEY.

CHANNEL-FLAP-TURNING MACHINE.

Application filed February 28, 1922. Serial No. 540,037.

The present invention relates to channel flap turning machines and is herein illustrated as embodied in a machine for turning back the channel flaps of soles for McKay shoes. Certain features of the invention, however, are adapted for embodiment in machines for operating upon other kinds of soles.

In the manufacture of boots and shoes of the McKay type in which the soles are united to the uppers or vamps by fastenings inserted from the outer finished surface of the sole, it is customary to use channeled soles, a flap being formed in channeling, which flap is turned over backwards and pressed down, so as to leave the channel open for the reception of the fastenings, the flap being turned back again to its original position after the sole and vamp are united.

In order to facilitate the operation of securing the sole to the shoe it is desirable to have the channel flap turned and set in a substantially flat position closely adjacent to the face of the sole to insure that the flap will not interfere with the action of the needle in the McKay sewing machine, and it is further desirable that the required turning and setting of the lip shall be accomplished without frictional rubbing of the sole margin such as would tend to burn or otherwise injure it.

One object of the present invention is to provide a channel flap turning machine having an improved construction and mode of operation enabling it to accomplish the results above set forth.

With this object in view one feature of the invention consists in the provision of a channel flap turning machine having a rotary work feeding member, an independently mounted flap turning member arranged to rotate in a plane parallel to the plane of rotation of the feeding member, and means for rotating the flap turning member at a higher speed than the work feeding member. As shown, the rotary work feeding member consists of an upper feed disk arranged so that its lower side face will engage the upper surface of the feather or marginal portion beneath the channel flap of a sole, and this disk is mounted in coaxial relation with the flap turning member and is arranged to co-operate with a lower feed wheel to grip and feed the mar-

gin of the sole. By providing separate members for turning the channel flap and for co-operating with the lower feed wheel in the feeding of the work, the flap turning member may be constructed and arranged so that it will engage the channel flap only, and so that it may be rotated at a much higher speed than would be practicable if it were designed also to have feeding engagement with the sole margin. The relatively high speed of the flap turning member enables the latter more effectively to turn the channel flap over against the face of the sole and to set the flap in a substantially flat position while the relatively slow speed of the upper feed disk insures against injurious rubbing contact with the sole margin.

Other features of the invention relate to the yielding mounting of the flap turning member, and to the provision in this member of a recess to receive the upper feed member to facilitate operation upon soles having thin channel flaps.

The invention further resides in other features of construction and combinations of parts hereinafter described and claimed, the advantages of which will be apparent to those skilled in the art.

Other objects and novel features of the construction and arrangement of parts constituting our invention will appear as the description of the invention progresses.

In the accompanying drawings illustrating the preferred embodiment of our invention,

Fig. 1 is a view in side elevation of the machine;

Fig. 2 is a view in front elevation thereof;

Fig. 3 is an enlarged sectional detail of the head of the machine;

Fig. 4 is a sectional plan view on the line 4—4 of Fig. 1, and

Fig. 5 is a sectional detail on the line 5—5 of Fig. 4.

Referring to the drawings 10 designates a base having formed integral therewith an upwardly extending portion 11 in which is rotatably mounted a horizontal shaft 12 provided at one end with a pulley 13, by means of which power may be transmitted to the shaft from any suitable source of power, and at the other end with a bevel gear 14.

A bearing member 15, formed integral with the portion 11 and at the top thereof, is provided with a sleeve or bushing 16, this sleeve or bushing being held in place by a set screw 17. The upper end of the bore of the sleeve or bushing 16 is threaded to receive an adjusting bolt 18, a check nut 19 on the bolt co-operating with the upper end of the sleeve or bushing 16 to hold the bolt in adjusted 5 position for a purpose to be hereinafter described. Near the lower end of the portion 11 is a second bearing member 20, in which is rotatably mounted the lower end of a hollow shaft 21, the upper end of this shaft 10 terminating at a point below the lower end of the sleeve or bushing 16 and being rotatably mounted in a sleeve 22 threaded into and adjustable in a bearing member 23 secured to the portion 11 by a bolt 24. Secured to the hollow shaft 21 by a set screw 15 25 is a bevel gear 26 which meshes with and is driven by the bevel gear 14 on the driving shaft 12. A coil spring 27 surrounding the hollow shaft 21 and located between the 20 upper end of the bevel gear 26 and the bottom of the threaded sleeve 22, holds the bevel gears 26 and 14 in engagement with each other. The spring 27 also functions to cushion the turning roll 64, permitting it to 25 yield upwardly relatively to the disk 63 to accommodate different thicknesses of channel flap without requiring readjustment of the parts. Rotatably mounted in the sleeve or bushing 16 and the hollow shaft 21 is a shaft 28 limited in its downward motion by a bushing 29 secured to the shaft by a set screw 30, while a bevel gear 31 is secured to the shaft, adjacent the portion 15, by a set screw 32. Further, the bolt 18 engages the top of the shaft 28 to limit its upward movement. The bevel gear 31 meshes with a bevel gear 33 secured to a shaft 34 which is rotatably mounted in the portion 11 parallel to the shaft 12. A suitable bearing on the portion 11 supports the end of the shaft 34 at the end remote from the bevel gear 33, and secured to the shaft 34 is a worm wheel (not shown) which meshes with and is driven by a worm 36 secured to the top of a shaft 37 which is rotatably mounted in bearings 38, 39 and 40 formed integral with the portion 11. Secured to the shaft 37, adjacent to the bearing 39, is a worm wheel 41 driven by a worm (not shown) secured to the drive shaft 12. The lower end of the shaft 37 extends downward below the portion 11, as clearly shown in Fig. 1, and has attached at its lower end a worm 42 which meshes with a worm wheel 43 secured to a shaft 44 mounted in a bearing 45 formed integral with the base 10, a collar 46 secured to the shaft by a set screw 47 preventing inward movement of the shaft. This shaft 44 is located at an angle with regard to the shaft 37 and is connected to a shaft 48 by a universal joint 49, 55 60 65 70 75 80 85 90 95 100 105 110 115 120 125 130

the shaft 48 being rotatably mounted in a bearing 50 slidably mounted in a frame member 53 that in turn is secured, by bolts 52, to a lug 72 that is adjustably mounted on portion 11. Formed integral with and at the lower end of the frame member 53 is an outstanding lug 54 in which is slidably mounted a bolt 55, the upper end of which is threaded into the bearing member 50 while to the lower end of which is attached the eye 56. Check nuts 57 on the upper end of the bolt 55 are utilized to adjust the tension of a coil spring 58 mounted on the bolt 55 between the check nuts 57 and lug 54, which spring tends to force the bearing member 50 to its uppermost position. Check nuts 59 on the lower end of the bolt 55 limit the upward movement of the bearing member 50. Secured to the eye 56 is a rod 60 which extends to the usual treadle (not shown). Secured to the outer and free end of the shaft 48, by screw 61, is a beveled corrugated feeding wheel 62 which is arranged to support the sole; secured to the lower end of the shaft 28 is a beveled disk 63 that co-operates with the feeding wheel; secured to the lower end of the hollow shaft 21 is a serrated flap turning member in the form of a roll or disk 64 that co-operates with both the beveled feeding disk 63 and the feeding wheel 62. 95 The feeding wheel 62 is of sufficiently small diameter to insure that it will not break down or flatten the more or less abrupt bend at the forward end of the shank portion of a molded insole. Secured to the bearing member 20 by a screw 65 is a guide 66 that co-operates with the channel flap turning roll 64. The periphery of the feeding wheel 62 may be transversely rounded, as shown in Fig. 1, the better to adapt the wheel to operate upon soles of certain types, such, for example, as soles for so-called cottage-shank shoes, in which the shank portion of the sole is molded so that it has more or less transverse curvature. When the feeding roll is thus rounded, the cross-sectional contour of its periphery will conform substantially to the transverse curvature of a molded sole so that the feeding wheel will contact with the sole substantially throughout the width of the wheel, and accordingly will not break down or destroy the molded transverse curvature of the sole. When, however, a flat portion of the margin of a sole is fed over a lower feeding wheel having a transversely rounded periphery, such as shown in Fig. 1, the wheel will have a much more restricted area of contact with the sole and consequently a minimum amount of resistance will be offered to the turning or swinging of the sole as it is fed along. An edge gage 80 is adjustably secured to the frame portion 11 to guide the sole by engagement with the edge of the feather. The flap turning roll 64 is countersunk or recessed to a sufficient 130

depth to receive the beveled disk 63, as clearly shown in Fig. 3, and the disk 63 may be adjusted relatively to such flap turning roll by means of the bolt 18. The periphery 5 of the disk 63 engages the shoulder at the root of the turned channel flap and thus has a gaging function supplementing that of the edge gage 80. By turning the bolt 18 the position of the feeding disk 63 relatively 10 to the recess in the flap turning roll 64 may be adjusted to vary the amount of projection of the disk 63 from said recess according to the thickness of the channel flap so that in cases where the channel flap is very thin the 15 disk may be raised until its feeding surface is located only slightly below the bottom of the flap turning roll. Such adjustment also varies the effective width of the peripheral face of the flap turning roll according to the 20 thickness of the shoulder at the base of the turned channel flap. The feeding wheel 62 need not necessarily be corrugated as shown inasmuch as good results may be obtained by using a wheel having a smooth feeding 25 surface. The wheel 62 being of comparatively small diameter, it has practically no tendency to flatten or destroy the mold of the sole.

It will be noted by reference to Figs. 1 and 30 2, that the shaft 28 is inclined at an angle to the perpendicular, and that shaft 48 is inclined at an angle to the horizontal, this construction making it possible to operate on a sole 69 that is held in a substantially horizontal plane, as the working face of the feeding wheel 62 is substantially horizontal. Further, the beveled disk 63 is held to the work at the most efficient angle, and it will be noted, by reference to Fig. 3, that the 35 contact of the feeding wheel 62 with the sole 69 is practically a line contact while the disk 63 engages the sole practically at only a single point. This latter feature makes it possible to turn the channel flap of different 40 styles of formed soles—such as soles for cottage shank shoes—without danger of deforming the soles. The turning of the flap is further facilitated by the shape of the radial teeth or work-engaging portions of the 45 flap-turning member, said teeth having their lower or operative surfaces inclined upwardly and outwardly, as shown in Fig. 3, so that as each tooth passes across the lip it functions to turn the lip by an easy cam 50 action which gently raises the lip and forces it back gradually. The tapering feeding wheel 62 is arranged with its larger end engaging the sole nearer the edge of the feather, and since the lineal speed of the 55 feeding surface of the wheel is greater at the large than at the small end, the feeding wheel will tend to impart a rotating or circular motion to the sole fed across it. This 60 action causes the sole to hug the edge gage 80 as the sole is fed and relieves the oper-

ator of the necessity of continuously and carefully pressing the sole against the edge gage. The tendency of the sole to rotate against the edge gage as it is fed also facilitates very materially the turning of the sole 70 at the toe and ball, the two critical points in the manipulation of the sole.

The frame member 53 is adjustable toward and from the base 10 and portion 11 by means of a bolt 70 screwed into the portion 75 11 and co-operating with the slot 71 in the rearwardly extending lug 72 on the member 53 and by a bolt 73 in the base 10 engaging with a rearwardly extending rod 74. Fingers 67 and 68, on either side of the 80 shaft 28, see Fig. 4, are arranged in guide-ways 75 and 76 respectively, gibs 77 and 78 secured to the portion 11 by bolts 79 holding the fingers in adjusted position. The free extremity of the finger 67 extends into 85 the channel forward of the flap-turning roll and is shaped to raise the channel flap sufficiently to insure that it will be properly engaged and turned by said roll. The finger 68 serves to prevent the portion of the sole 90 which has been operated upon from curling upwardly and thus insures against injury thereto by the flap-turning roll.

The various worms and worm wheels are so proportioned that the hollow rotatable 95 shaft 21 and therefore, the serrated flap-turning roll 64, rotates considerably faster than the beveled disk 63 and the feeding wheel 62, these two latter rotating at practically the same speed. Thus the contact 100 of the periphery of the disk 63 with the base of the channel flap is substantially a rolling contact and there is no frictional rub or tendency to cut, glaze or burn the flap.

The operation of our improved machine 105 will be readily understood. The operator adjusts the disk 63, flap-turning roll 64, feeding wheel 62, and fingers 67 and 68 to function properly on the size and type of sole of which is desired to turn the 110 flap. The machine is then started in motion, and the treadle (not shown) is operated to lower the feed wheel 62 to allow the sole 69 to be placed in position, as shown in Fig. 3. There being but 115 a single line contact between the sole 69 and the feed wheel 62, while the beveled disk 63 touches the sole at but a single point, there is no possibility of deforming the sole whatever the shape may be. The guide 66 receives the turned over flap as it leaves the 120 turning roll and provides a substantial bearing area upon the turned flap at this point, thus helping to guide the sole 69 positively and surely, and preventing the sole from 125 being thrown out of engagement with the rapidly rotating serrated turning roll 64. The guide 66 is particularly useful when soles having more or less pointed toes are 130 being operated upon to prevent the flap-

turning member from tearing or injuring the flap at the toe of the sole. The guide 66 serves to retain the pleated effect imparted to the flap by the turning member at 5 the toe of the sole.

While we have necessarily shown and described the preferred embodiment of our invention somewhat in detail, it is to be understood that we may vary the size, shape, 10 and arrangement of parts constituting our machine within wide limits without departing from the spirit of the invention.

Having thus described our invention, what we claim as new and desire to secure 15 Letters Patent of the United States is:

1. In a channel flap turning machine, the combination of a feeding wheel, a feeding disk co-operating therewith to grip a sole to be operated upon, means for simultaneously rotating said wheel and disk in the 20 same direction at their points of contact with the sole, and a channel flap turning disk concentric with said feeding disk and rotatable at a higher rate of speed than the 25 said wheel and feeding disk to turn the channel flap on the sole as the same is fed therethrough.

2. In a channel flap turning machine, the combination of a base, a feeding wheel 30 mounted thereon and having its axis of rotation at an angle with the horizontal, a pair of shafts mounted in said base concentric with each other and making an angle with the perpendicular, a feeding disk 35 mounted on one of said shafts and co-operating with the feeding wheel, and a channel flap turning disk mounted on the other of said shafts and co-operating with the feeding 40 wheel and feeding disk to turn the channel flap of a sole being fed therethrough.

3. In a channel flap turning machine, the combination of a base, a feeding wheel mounted therein and having its axis of rotation at an angle with the horizontal, a pair 45 of shafts mounted in said base concentric with each other and making an angle with the perpendicular, a feeding disk mounted on one of said shafts and co-operating with the feeding wheel, and a channel flap turning disk mounted on the other of said shafts and co-operating with the feeding wheel and feeding disk to turn the channel flap of a sole being fed therethrough, and a guide 50 engaging said sole.

4. In a channel flap turning machine, the combination of a base, a feeding wheel mounted therein and having its axis of rotation at an angle with the horizontal, a pair 55 of shafts mounted in said base concentric with each other and making an angle with the perpendicular, a feeding disk mounted on one of said shafts and co-operating with the feeding wheel, a channel flap turning disk mounted on the other of said shafts 60 and co-operating with the feeding wheel and 65

feeding disk to turn the channel flap of a sole being fed therethrough, and a guide adjustably mounted in said base for engagement with the turned flap for guiding the sole through the said wheel and feeding disk. 70

5. In a channel flap turning machine, the combination of a base, a feeding wheel and a feeding disk rotatably mounted therein with their axes of rotation making an angle with each other and with the horizontal and perpendicular respectively, said disk being arranged with its side face overlying the feather of a sole to be operated upon and engaging the feather throughout a restricted area less than that of the portion 80 of the disk overlying the feather, a flap turning wheel coaxial with said disk and movable independently thereof, and means for rotating said wheel and disk at substantially the same surface speed. 85

6. In a channel flap turning machine, the combination of work supporting and feeding means, a flap turning member provided with a plurality of radial flap turning projections having work engaging surfaces inclined upwardly from their inner to their outer extremities, and means for yieldingly holding the flap turning member in operative engagement with the work. 90

7. In a channel flap turning machine, the combination of a feeding wheel, a feeding disk co-operating with said wheel to feed the work, said disk having its axis of rotation inclined relatively to the axis of said wheel, a rotary channel flap turning member having its axis of rotation coincident with the axis of said disk, means for supporting said parts, means for rotating said wheel and disk at substantially the same peripheral speed, and means for rotating said flap-turning member at a higher rate of speed than said wheel and disk. 100

8. In a channel flap turning machine, the combination of a feeding wheel, a feeding disk having a side face arranged to co-operate with said wheel to feed the work, a rotary flap-turning member having a recess to receive the other side of said disk, means for rotating said parts, and means for yieldingly urging said member toward the work. 110

9. In a channel flap turning machine, the combination of a feeding wheel, a feeding disk arranged with a side face adapted to co-operate with said wheel to feed the work, a rotary flap-turning member adjacent to the other side of said disk, means for rotating said parts, a spring for pressing said member toward the work, and means for adjusting the tension of the spring to vary the pressure of said member against the 120 work. 125

10. In a channel flap turning machine, the combination of a feeding wheel, a feeding disk for co-operating with said wheel to feed the work, a flap-turning member coaxial 130

with said feeding disk and yieldingly held against the non-feeding side of the latter, and means located at the same side of the work for supporting and rotating the feeding disk and the flap turning member.

11. In a channel flap turning machine, the combination of a feeding wheel, a shaft, a feeding disk fixed to said shaft and having a side face for co-operating with said wheel 10 to grip and feed the sole and a peripheral shoulder arranged to engage the base of the channel flap, a sleeve surrounding said shaft, a flap-turning member secured to said sleeve, and means for rotating said shaft and said 15 sleeve at different speeds.

12. In a channel flap turning machine, the combination with a flap-turning member having a recess, of work-feeding means comprising a disk rotatable independently of 20 the flap-turning member and capable of being received within said recess, said disk having a peripheral face of substantial width to engage the base of the channel flap after the flap has been turned to gage the 25 position of the sole relatively to the flap-turning member and to assist in the feeding of the work, and means for adjusting the position of the disk relatively to the recess in the flap-turning member.

13. In a channel flap turning machine, the combination of a feed disk having a peripheral shoulder arranged to engage the base of the channel flap and bulging side faces one of which is adapted to engage the 35 sole adjacent to the inner edge of the channel, and a flap-turning disk coaxial with said feed disk and recessed to receive the other bulging side face of the flap-turning disk.

14. In a channel flap turning machine, the combination of rotatable members co-operating to grip and feed the sole, a rotary tool coaxial with one of said members and mounted for rotary movement independently of said members and for yielding bodily movement for turning the channel flap as the sole is fed, and means on one 45 of said feed members for engaging an area of substantial width along the base of the channel flap after the flap has been turned to gage the position of the sole relatively to the flap-turning means and to assist in the feeding of the sole.

15. In a channel flap turning machine, the 55 combination of rotatable members co-operating to grip and feed the sole, a rotary wiper member for turning the channel flap as the sole is fed, an edge gage, and a guide adapted to engage the turned channel flap 60 to assist in maintaining the sole against the edge gage.

16. In a channel flap turning machine, the combination of rotatable members co-operating to grip and feed the sole, a flap- 65 turning wheel for turning the channel flap

as the sole is fed, an edge gage, and a guide associated with the flap-turning means having a recessed face shaped to receive the turned flap as it is puckered or pleated at the toe to protect said portion of the flap 70 from being disarranged or injured by the flap-turning means.

17. In a channel flap turning machine, the combination of a feeding wheel, a feeding disk co-operating therewith to grip and feed 75 a sole interposed between them, a channel flap turning disk concentric with said feeding disk, and means for rotating the flap-turning disk in the same direction as the feeding disk but at higher speed.

18. In a channel flap turning machine, the combination of a feeding wheel, a feeding disk co-operating therewith to grip and feed a sole interposed between them, a channel flap turning disk concentric with said feeding disk, means for rotating the flap-turning disk at higher speed than the feeding disk, and a plow for raising the channel flap into position to be engaged by the flap-turning disk.

19. In a channel flap turning machine, the combination of a feeding wheel for engaging the unlipped face of a sole, a feeding disk for engaging the feather beneath the channel flap, said wheel and disk having 95 their rotational axes inclined relatively to the horizontal and their work-engaging faces co-operating to grip and feed the sole, and a yieldingly mounted rotary channel flap turning member arranged with its axis coincident with the axis of the feeding disk driven at a speed different from that of said feed members.

20. In a channel flap turning machine, means including a rotary member for feeding the work, and an independently mounted rotary member concentric with and closely adjacent to said feeding member for turning back the channel flap.

21. In a channel flap turning machine, means including a rotary disk for feeding the work, and a rotary flap-turning disk concentric with said feed disk and driven at a higher speed than said disk.

22. In a channel flap turning machine, the combination of a rotary work feeding member, an independently mounted flap-turning member arranged to rotate in a plane parallel to the plane of rotation of the work feeding member, and means for rotating the flap-turning member at a higher speed than the work feeding member.

23. In a channel flap turning machine, the combination of a rotary work feeding member, an independently mounted flap-turning 125 member coaxial with said feeding member, and means for rotating the flap-turning member at a higher speed than the work feeding member.

24. In a channel flap turning machine, the 130

combination of a feeding wheel arranged for peripheral engagement with one side of the material beneath the flap of a channeled sole, a feeding disk arranged with one face opposed to a portion of the periphery of said wheel for engagement with the other side of said material, yielding means for maintaining said members in gripping engagement with the sole, a flap-turning member arranged to rotate in a plane parallel to the plane of rotation of the feeding disk, and means for rotating said wheel and said disk at substantially the same surface speed at their points of engagement with the sole and for rotating the flap-turning wheel at a substantially higher rate of speed.

25. In a channel flap turning machine, a feeding wheel, a feeding disk for engaging the margin of a channeled sole beneath the channel flap and co-operating with the feeding wheel to grip the sole beneath the peripheral face of the wheel and the side of the disk, and a yieldingly mounted flap-turning member arranged to rotate in a plane parallel to the plane of rotation of the feeding disk.

26. In a channel flap turning machine, a work supporting feeding wheel, a feeding disk for engaging the feather of a channeled sole beneath the channel flap and co-operating with the feeding wheel to grip the feather between the peripheral face of the wheel and the side of the disk, a flap-turning member arranged to rotate in a plane parallel to the plane of rotation of the feeding disk, and means located at one side of the plane of the work for supporting the feeding disk and the flap-turning member.

27. In a channel flap turning machine, the combination of a feeding wheel, a feeding disk co-operating with said wheel to feed the work, said disk having its axis of rotation inclined relatively to the axis of said wheel, a rotary channel flap turning member having its axis of rotation coincident with the axis of said disk, and means for rotating the feeding wheel and the flap turning member in timed relation.

In testimony whereof, we have signed our names to this specification.

ARTHUR J. LANGLOIS.
WILLIS H. MANSFIELD.
